[57] CLAIM

The ornamental design for a hand-held medical diagnostic instrument handle, as shown and described.

DESCRIPTION

FIG. 1 is a perspective view of a hand-held medical diagnostic instrument handle showing our new design;

FIG. 2 is a top plan view;

FIG. 3 is a bottom plan view;

FIG. 4 is a left side elevational view thereof; and,

FIG. 5 is a front elevational view thereof.

The broken line showing the handle adapter in FIG. 5 is for illustrative purposes only and forms no part of the claimed invention.
